R. H. RICE.
STOP MOTION FOR GOVERNORS.

No. 536,156.

Patented Mar. 19, 1895.

UNITED STATES PATENT OFFICE.

RICHARD H. RICE, OF PROVIDENCE, RHODE ISLAND, ASSIGNOR TO THE RICE & SARGENT ENGINE COMPANY, OF SAME PLACE.

STOP-MOTION FOR GOVERNORS.

SPECIFICATION forming part of Letters Patent No. 536,156, dated March 19, 1895.

Application filed January 4, 1895. Serial No. 533,835. (No model.)

To all whom it may concern:

Be it known that I, RICHARD H. RICE, a citizen of the United States, residing at Providence, in the State of Rhode Island, have invented a new and useful Improvement in Stop-Motions for the Governors of Steam-Engines, of which the following is a specification.

The object of my invention is to provide positive means for automatically shutting off the steam from the engine, upon the occurrence of any accident which results in stopping the rotation of the governor, while the engine is continuing its action; and my invention consists in the employment of a reversely grooved cam in combination with a link movement, between the governor and the cut-off valve gear, as hereinafter fully set forth.

In the accompanying drawings:—Figure 1, represents a side elevation of a steam engine governor provided with my improvement. Fig. 2, represents a detail side view taken at right angles to the view shown in Fig. 1. Fig. 3, represents a detail top view the governor being removed.

In the drawings, A represents the fixed standard which serves to support the upright shaft, B, of the governor C, which shaft is driven by means of a pulley secured to the horizontal shaft D, from which connection is made with the upright shaft B by means of a suitable bevel-gear and pinion. The head i of the standard A is provided with the forked arm H, to which is pivoted the lever I, which lever is preferably made in two parts as indicated by the line a, in Fig. 3, the said parts being held together by means of the bolts b and c. The two parts of the lever I, are made to inclose the sliding sleeve J of the governor, the said sleeve being provided with the circumferential groove d, within which is placed the loose ring e, as indicated by dotted lines in Fig. 1, the said ring e being provided with perforations which are adapted to receive the studs f, f, extending inwardly from the opposite parts of the lever I, so that upon the rise and fall of the sleeve J, a corresponding movement will be imparted to the lever I.

The lever I is connected at its short arm g, with the piston rod K, of the oil cylinder L, which serves to steady the action of the gov-

ernor, the said rod being provided with the attached weight rest M; and to the end of the long arm h of the lever, is connected the pendent weight rest M', for effecting the proper adjustment of the action of the governor. 55 To the side of the head i of the standard A, is secured the plate G, the said plate being provided with the reversely directed cam-groove R, the upper portion k' of which extends downwardly and outwardly from the standard A, while the reversely inclined lower portion k², extends downwardly and inwardly toward the standard. To the side of the long arm of the lever I, is jointed the cam-link N, the said link N being provided with a roller-carrying stud n, which enters the cam-groove R; and to the lower end of the link N, is jointed the rod P, by means of which proper connection is made with the cut-off valve gear of the engine. Upon the screw-stud r at 70 the side of the head i of the standard A, is placed the loose arm Q, which may be turned up as shown in Fig. 2, to form a bearing rest for the lever I in properly supporting the governor at the ordinary stopping and starting 75 of the engine, but which when the engine is in operation, is to be turned downward to the position shown in Fig. 1 so as to provide for the resulting abnormal downward movement of the lever I, at the slipping or breaking of the driving-belt.

When the governor is operating under the normal conditions, the roller stud n in the cam-groove R of the plate G, will be held in the inclined upper portion k' of said groove 85 and in this case the valve-gear will be operated to close the valve, by the action of the cam-groove R upon the link N and rod P, at the rise and fall of the governor through the limit of its normal variation, but upon the 90 loosening or breaking of the belt of the governor, so that the governor is caused to sink below the proper position for its lowest extreme of normal variation, then the stud n will be caused to enter the reversely inclined 95 lower portion k² of the cam-groove R, and the action of the said lower portion k² upon the link N and rod P, will be such, as to cause the reverse movement of the said link N and rod P, to that before produced by the downward 100

movement of the governor, and this reverse action will serve to cause the closing of the valves of the engine, to shut off the steam.

It is to be understood that the reversely inclined cam-groove R, may be arranged in a reverse position to that shown in Fig. 1, by making the proper connection with the valve-gear of the engine to compensate for the resulting oppositely directed action upon the link N and rod P, at the rise and fall of the governor.

I claim as my invention—

1. In a stop motion for the governor of a steam engine, the combination of the governor, and a depending cam-link, operatively connected with the governor and the valve-gear, with the reversely inclined cam adapted

to change the transmitted action of the governor at its abnormal downward movement, substantially as described.

2. In a stop motion for the governor of a steam engine, the combination of the governor, with the lever operatively connected with the sleeve of the governor, the reversely inclined cam, adapted to change the transmitted action of the governor at its abnormal downward movement, and the cam-link operatively connected with the lever and the valve-gear, substantially as described.

RICHARD H. RICE.
